UNITED STATES PATENT OFFICE.

MEYER GREENBURG, OF KEARNEY, NEW JERSEY.

DESIGN FOR A SHAVING-BRUSH HOLDER.

Application filed October 10, 1922. Serial No. 3,925. Term of patent 3½ years.

To all whom it may concern:

Be it known that I, MEYER GREENBURG, a citizen of the United States, and a resident of Kearney, in the county of Hudson and State of New Jersey, have invented a new, original, and ornamental Design for Shaving-Brush Holders, of which the following is a specification, reference being had to the accompanying drawing, forming part thereof.

I claim:

The ornamental design for a shaving brush holder, as shown.

MEYER GREENBURG.
